UNITED STATES PATENT OFFICE.

WALTER K. HARRINGTON, OF ANDOVER, NEW JERSEY, ASSIGNOR TO
CONSOLIDATED GAS COMPANY, OF NEW YORK, N. Y., A CORPO-
RATION OF NEW YORK.

GAS-METER.

No. 814,958.

Specification of Letters Patent.

Patented March 13, 1906.

Application filed November 13, 1905. Serial No. 286,975.

To all whom it may concern:

Be it known that I, WALTER K. HARRINGTON, a citizen of the United States, residing in Andover, New Jersey, have invented cer-
5 tain new and useful Improvements in Gas-
Meters, of which the following is a full, true,
and concise specification.

My invention relates to gas-meters, and
pertains more particularly to certain herein-
10 after-described improvements in the relative
disposition of the several parts and in the
structure and operation thereof which look
toward an increase in the capacity of the me-
ter and simplicity and economy in the cost of
15 manufacture and repair.

The invention is illustrated in the accom-
panying drawings, which form a part of this
specification, and in which like parts are re-
ferred to by like reference-numerals through-
20 out.

Figure 1 is a plan view of a meter embody-
ing my improvements having the central top
cover or cap removed. Fig. 2 is a vertical
sectional view centrally through the bellows,
25 but showing the gearing, valves, and rock-
shafts in elevation. Fig. 3 is a horizontal
sectional view, partly on line 3 3 of Fig. 2 and
partly on line 4 4 of said figure, with certain
parts broken away and shown in dotted
30 lines. Fig. 4 is a detail showing the location
of the inlet and outlet pipes and the struc-
ture of the valve-seats, one of the latter be-
ing shown in horizontal section; and Fig. 5 is
35 a diagrammatic view intended to simplify
the ready understanding of the meter and to
illustrate in one figure the several valves and
ports and the operation thereof.

The new meter comprises a main casing
which has two removable side plates 22 and
40 a removable cap-plate 3. The side plates 22
afford a means of access, respectively, to the
two sides of the motor-chamber and the cap-
plate 3 to the valve-gearing contained in the
distributing-chamber, both side plates and
45 cap-plate being removable and soldered in
place when the meter is in condition for op-
eration. The horizontal partition or floor 5
is secured gas-tight within the main casing
and divides the same into the motor and dis-
50 tributing chambers just mentioned.

The motor mechanism employed in this in-

vention is similar in every respect to motor
mechanisms now in general use in gas-meters
and comprises two bellows 6 and 7, respec-
tively mounted on opposite sides of a vertical
dividing wall or septum 8, both bellows being
provided with stiffener-plates 9, which are
connected, by means of the posts 10, with
crank-arms 11, carried, respectively, by
rock-shafts 12 in such manner that inflation
and deflation of the bellows will cause the
said shafts to rock in their bearings. Both
bellows are also guided, by the usual guide-
rods 13 13, which are hinged to the bottom
of the casing and play in suitable eyes 14 on
the stiffener-plates 9. The upper extremi-
ties of the rock-shafts 12 pass through suit-
able stuffing-boxes 15, Fig. 2, secured to the
floor 5 on the upper surface thereof, and are
provided with cranks 16, which are each
connected by links 17 with the adjustable
wrist-pin 18 of a vertical crank-shaft 19.
The latter is journaled in a vertical bracket
20, properly secured by the screw 21 to the
floor 5 and on the upper surface thereof.
The said crank-shaft carries a worm 22, mesh-
ing with a worm-wheel 23, carried by an ar-
bor 24, which latter is journaled at one end in
the bracket 20 and is supported at its other
end in the dial mechanism 25. The dial
mechanism may be of the usual construction,
consisting of a train of gears with pointers
and dials. (Not shown, but which are ex-
posed to view through a suitable window from
the outside of the main casing.) The hinged
cover-plate 26 normally covers the glass of
the window to protect it from injury. The
dial mechanism is wholly contained within
the gas-distributing chamber of the meter,
and although a stuffing-box 27 may be pro-
90 vided for excluding gas from the casing of the
dial mechanism yet such stuffing-box is not
required and the casing of the dial mech-
anism may be an open or skeleton casing, if de-
sired. The said dial-casing, moreover, may
95 be appropriately secured, as by soldering, to
the top of the horizontal floor 5 adjacent to
the window or to the side wall.

Gas is supplied to the motor mechanism by
means of two slide-valves 30 31, operated by
the vertical crank-shaft 19, as will be pres-
ently described. The valve-seats 32 of each

valve are located within the gas-distributing chamber, being secured to the upper surface of the horizontal floor 5 thereof. Each valve-seat is provided with a forward valve-port 33-34, Fig. 4, respectively, opening into the tapering conduits 35 and 36, which latter have isolated communication through the horizontal floor 5 with the inlet-passages 37 and 38 of the bellows 6 and 7, respectively. The conduits 35 and 36 are formed of sheet metal soldered to the floor 5 on each side of the vertical crank-shaft 19. The valve-ports 39 and 40 at the opposite ends of the valve-seats 32 lead directly through suitable isolated openings in the floor 5 into the compartments of the motor-chamber on the outside of the bellows therein. The middle valve-ports of each valve-seat 32 open directly into an outlet-chamber 41, which is located in the angle between the two valve-seats and is formed of two similar plates 42 and a plate 43, which serve to close in or confine the space between the said valve-seats and the walls of the main casing, a top plate 44 being soldered to the top of the plates 42-43 and the valve-seats 32, as shown in Fig. 3. An outlet-pipe 45, soldered to an aperture in the center of plate 44, provides an escape or outlet pipe which passes through the distributing-chamber to the exterior of the casing. The valves proper (indicated by numerals 46 and 47 in Fig. 3 and which coöperate with the valve-seats 32 just described) are superposed thereon and guided to move in a straight direction by means of two guide-rods 48 and 49. The guide-rods 48 are secured to the proximate sides of the valves 46 and 47 adjacent to the outlet-box 41 and extend rearwardly, passing through the guiding-posts 50, the latter being secured directly to the horizontal floor 5. The guide-rods 49 are located on the sides of the valves opposite the rods 48 and extend forwardly, passing through the guiding-posts 51, the latter being secured to the tops of the conduit-tubes 35 and 36, respectively. Each valve is provided with pins 52 and pitman-rods 53, connecting the same with the crank-shaft 19, and the valves and their valve-seats are placed upon the horizontal floor 5 at an angle approximating ninety degrees, this being an appropriate angle for communicating to them from the uniformly-rotating crank-shaft 19 their properly-timed movement. By the arrangement of the connecting-rods 48 and 49 on the sides of the valves instead of in alinement with their axes, as has heretofore been the custom, I am permitted to use larger valves with a longer stroke relatively to the size of the chamber in which they work, and therefore increase the capacity of the motor without increasing its external dimensions. In the reciprocation of the valves the said guide-rods play in their respective guiding-posts, but the rods 48 do not come in contact with the walls of the cas-

ing; nor do the rods 49 interfere with each other or with the action of the crank of the valve-shaft 19. The latter rods, however, extend beyond the said valve-shaft and are disposed below the plane of the pitman 53. 70

The inlet-pipe 55 enters the meter from the top similarly to the pipe 45 and debouches directly into the gas-distributing chamber, which, as above mentioned, contains all of the valve mechanism and valve-gearing, as well as the dial mechanism. As will be seen from Fig. 1, both the inlet and the outlet pipes are located on the top of the meter within the vertical boundaries thereof and do not, therefore, obstruct or hinder the connection of the meter in confined quarters. 75

In operation the gas to be measured entering through the inlet-pipe 55 emerges directly into the gas-distributing chamber. Assuming the valves 46 and 47 to be in the relative positions indicated by the foreshortened and diagrammatic section of Fig. 5, it passes directly from the gas-distributing chamber through the uncovered valve-port 40 and the aperture in the floor 5 into the chamber outside of the bellows 7 and by acting thereagainst collapses the same, forcing the gas in the interior thereof out through the passage 38 of the conduit 36, valve-seat port 34, valve 47, and valve-seat port 32 into the outlet-box 41, from whence it escapes through the outlet-pipe. The collapsing movement of the bellows 7, however, imparts a rocking movement to its rock-shaft 12, which in turn produces a partial rotation of the valve-shaft 19, so that the valves 46 and 47 immediately begin to move through their respective traverses. In so doing the valve 46 uncovers the port 33 and allows gas to pass from the distributing-chamber through 95 said port and the conduit 35 into the interior of bellows 6, thereby inflating the same and causing the gas on the outside thereof to be expelled through the port 39, valve 46, and valve-seat port 32 into the outlet-box, from 100 which it escapes, as before. In the meantime and coincident with the latter part of this operation the valve 47 has been moved to its extreme rearward position, thereby covering port 40 and opening a communication through said port from the exterior of the bellows 7 to the outlet-box in obvious manner, at the same time admitting gas from the distributing-chamber into the interior of the bellows 7. A similar operation is 105 next effected by the valve 46, and the several operations are carried on successively in the above-described order, so that the bellows 110 impart the proper rocking movement to their rock-shafts and produce a continuous rotation of the valve-shaft 19. The rotation of the latter is transmitted by the worm and worm-wheel to the dial mechanism, and the latter is of course properly geared with respect 115 to the capacity of the several compartments 120 125 130

of the motor to register accurately the passage of gas through the meter. The crank-arm 54 of the latter is prevented from backward rotation by means of the usual latch-detent 56, carried by the bracket 20, above described.

Having described my invention, what I claim, and desire to secure by United States Letters Patent, is—

1. In a gas-meter, a main casing having a horizontal gas-tight partition therein dividing the same into an upper gas-distributing chamber and a lower motor-chamber, a vertical valve-operating shaft journaled and contained entirely within said gas-distributing chamber at about the center thereof, slide-valves for the motor disposed within said gas-distributing chamber and upon said partition at an angle to each other and pitman-rods connecting said valves with said vertical shaft, in combination with a double bellows-motor in the motor-chamber adapted to rotate said shaft and horizontal conduits disposed on the upper surface of said horizontal partition on opposite sides of said

valve-shaft and leading respectively from the valves to the interior of said bellows.

2. In a gas-meter, a main casing having a horizontal gas-tight partition therein dividing the same into upper and lower chambers, a motor mechanism in the lower chamber, two slide-valves mounted on said partition within said upper chamber, said valves being disposed at an angle to each other, in combination with an outlet-box formed on the upper surface of said horizontal partition between the valves and having communication with the lateral exhaust-ports of each of them, and an outlet-pipe connected to the top of said outlet-box and leading through the top of the main casing, said pipe being located within the vertical boundary of the meter.

In testimony whereof I have signed my name to this specification in the presence of two subscribing witnesses.

WALTER K. HARRINGTON.
